UNITED STATES PATENT OFFICE.

JOHN J. GOTTSCHALK, OF TAUNTON, MASSACHUSETTS.

DEVICE TO PREVENT HENS FROM SETTING.

1,321,819.

Specification of Letters Patent.

Patented Nov. 18, 1919.

Application filed June 20, 1919. Serial No. 305,629.

To all whom it may concern:

Be it known that I, JOHN J. GOTTSCHALK, a citizen of the United States, and a resident of Taunton, in the county of Bristol 5 and State of Massachusetts, have invented an Improvement in Devices to Prevent Hens from Setting, of which the following description, in connection with the accompanying drawings, is a specification, like characters on the drawings representing like parts.

This invention relates to devices to prevent hens or other fowl from setting.

In order that the principle of the invention may be readily understood, I have disclosed a single embodiment thereof in the accompanying drawing, wherein—

Figure 1 is a view of a hen having my invention applied to one leg;

Fig. 2 is a plan view of that form of my invention herein disclosed;

Fig. 3 is a side elevation thereof;

Fig. 4 is a vertical section on the line 4—4 of Fig. 2; and

Fig. 5 is a transverse section thereof upon the section line 5—5 of Fig. 3.

In modern poultry farms, it is highly desirable to provide devices for preventing hens from setting, but so far as I am aware 30 no satisfactory device has as yet been devised. Upon such farms the present day incubators and brooders are found to be far more reliable for the hatching of eggs and care of young chickens. I have ascertained from extensive investigations that 35 the average hen will, if permitted, set about three months a year. If this can be prevented wholly or substantially so and the hens throughout most of that time would 40 continue to lay, it is evident that the egg production would be largely increased.

An important object of my invention is to provide a device serving this purpose, which can be worn by the hen without substantial 45 inconvenience and without any detriment or ill effects whatever. It has heretofore been proposed to prevent hens from setting by applying a device at the joint of the leg wholly to prevent bending the joint.

50 A device of this sort, it is obvious, is objectionable, as it interferes with the freedom of movement of the hen when not setting. In accordance with the preferred embodiment of my invention I provide a device to be 55 applied to the leg preferably above or below the hock joint. I have found that a

single device is sufficient to prevent most hens from setting, but in extreme cases two of the devices may be employed, one upon each leg. In its preferred embodiment the 60 device of my invention comprises a ball like piece 1 of suitable material, such, for example, as rubber, though other materials may be employed, such as felt. Preferably, however, I employ a substance that is substantially yielding. The shape or form of the device may be varied within the scope of my invention, and within the scope thereof the device may be used at or over the hock joint. 70

The ball-like piece or member 1 is preferably resilient in and of itself, but if desired and as herein disclosed I embed therein in any suitable way a split spring ring 2 of metal or other suitable material which 75 serves to hold the ball or part 1 in closed position. In order to permit the device to be placed upon the leg of the hen, it is provided with a preferably central hole 3 leading into which is a slit 4 permitting 80 the device to be sprung open and placed about the leg, after which it immediately assumes its closed position. Preferably upon its inner surface the device is provided with projections or teeth 5 here shown as 85 of substantially triangular form in cross section, between which are preferably spaces 6 permitting air circulation through the device and preventing overheating of the leg or the adherence of dirt or other foreign 90 matter. The teeth or projection 5 are preferably relatively narrow along their lines of contact with the leg and serve in effect as cushioning parts or members, since in its preferred embodiment the device is relatively 95 highly flexible. The device is of relatively little weight, but is of sufficient size so that if the hen attempts to set and in doing so attempts to fold or bend its leg up beneath its body, the device by coming 100 into contact with the part of the leg above or below the hock joint, as the case may be, will substantially prevent such action, or will permit it with such inconvenience that the hen will cease from its efforts and within 105 a short time will entirely give up the attempt. Extensive experiments made by me have demonstrated that the device will break any hen of the setting habit or inclination in twenty-four hours. It is unnecessary, 110 though it is within the scope of my invention, to provide any supplemental means to

retain the device in position, since the inherent elasticity thereof is sufficient to retain it in place.

The teeth or projections 5 being relatively soft and yielding, do not chafe the leg, and hence the device is worn without any ill effects whatever and with a minimum of inconvenience.

The teeth 5 engage the leg with sufficient friction to hold the device in position. Preferably the openings 6 are formed as passages radiating from the central opening 3, but obviously air passages may be afforded in any other suitable manner.

Having thus described one illustrative embodiment of my invention, I desire it to be understood that although specific terms are employed, they are used in a generic and descriptive sense and not for purposes of limitation, the scope of the invention being set forth in the following claims.

Claims—

1. A device of the character described consisting of a member having a substantially uninterrupted resilient surface, and adapted to be worn above or below the hock joint of a fowl to prevent bending the leg sufficiently to permit setting.

2. A device to prevent hens from setting consisting of a substantially resilient member having a cushioning engagement with the leg, said member being of a size to be brought by attempted bending of the legs for setting into discomforting contact with the leg at a point somewhat removed from that part of the leg encircled thereby.

3. A device to prevent hens from setting consisting of a member having a series of inwardly directed cushioning teeth or projections to engage the leg, said member being of a size to be brought by attempted bending of the legs for setting into discomforting contact with the leg at a point somewhat removed from that part of the leg encircled thereby.

4. A device to prevent hens from setting consisting of a member having a series of spaced, inwardly directed, cushioning formations to engage the leg and retained in position by friction, said member being of a size to be brought by attempted bending of the legs for setting into discomforting contact with the leg at a point somewhat removed from that part of the leg encircled thereby.

5. A device of the character described to prevent hens from setting consisting of a ball-like member adapted to encircle the leg and having one or more passages there-

through for air circulation, said member being of a size to be brought by attempted bending of the legs for setting into discomforting contact with the leg at a point somewhat removed from that part of the leg encircled thereby.

65

6. A device to prevent hens from setting consisting of a ball-like leg encircling member having a central passage and split to permit it to be opened and applied to the leg of a hen, said member being of a size to be brought by attempted bending of the legs for setting into discomforting contact with the leg at a point somewhat removed from that part of the leg encircled thereby.

7. A device to prevent hens from setting consisting of a ball-like leg encircling member of rubber having cushioning teeth to engage the leg, said member being of a size to be brought by attempted bending of the legs for setting into discomforting contact with the leg at a point somewhat removed from that part of the leg encircled thereby.

75

8. A device to prevent hens from setting consisting of a ball-like leg encircling member 1 having spaced cushioning teeth 5 adapted frictionally to engage the leg of the hen, said member being of a size to be brought by attempted bending of the legs for setting into discomforting contact with the leg at a point somewhat removed from that part of the leg encircled thereby.

85

9. A device to prevent hens from setting consisting of a ball-like leg encircling member 1 of rubber having a central opening 3 95 and radiating air passages 6, said device having a slit 4 permitting application thereof to the leg, said member being of a size to be brought by attempted bending of the legs for setting into discomforting contact 100 with the leg at a point somewhat removed from that part of the leg encircled thereby.

90

10. A device to prevent hens from setting consisting of a ball-like leg encircling member 1 of rubber having a central opening 3 105 and radiating air passages 6, said device having a slit 4 permitting application thereof to the leg, and an embedded split, metal spring 2 to hold the device in closed position, said member being of a size to be 110 brought by attempted bending of the legs for setting into discomforting contact with the leg at a point somewhat removed from that part of the leg encircled thereby.

100

In testimony whereof, I have signed my 115 name to this specification.

JOHN J. GOTTSCHALK.
